UNITED STATES PATENT OFFICE

FRANK C. BAKER, OF McCAMEY, TEXAS

SHOCK ABSORBER FOR OIL-WELL PUMP RODS

Application filed October 5, 1928. Serial No. 310,633.

This invention relates to new and useful improvements in shock absorbers, and particularly to shock absorbers which are adapted for use in connection with oil well pump rods.

One object of the invention is to provide a shock absorber, of improved construction, which will readily absorb the shocks incident to the reciprocations of the walking beam.

10 Another object is to provide a device of this character wherein proper lubrication is given to the moving parts, and to the springs within the device, thereby greatly lengthening the life of the springs, and insuring the efficient 15 operation of the device.

A further object is to provide a device of this character wherein the parts are so constructed and arranged as to insure the proper alignment thereof, while at work.

20 Other objects and advantages will be apparent from the following description when taken in connection with the accompanying drawing.

In the drawing:

25 Figure 1 is an elevation of a shock absorber made in accordance with the present invention.

Figure 2 is an enlarged vertical longitudinal sectional view through the device.

30 Figure 3 is a horizontal sectional view on the line 3—3 of Figure 1.

Figure 4 is an elevation of a double shock absorber.

Figure 5 is a vertical sectional view of the 35 device shown in Figure 4.

Figure 6 is a horizontal sectional view on the line 6—6 of Figure 5.

Referring particularly to the accompanying drawing, 10 represents a metal shell 40 which has its upper end open, and has the upwardly extending central boss 11, in the bottom wall thereof, such boss lying within the shell. Cast in diametrically opposite sides of the shell, and extending throughout

45 the entire length of the shell, are the tapered bores 12, within which are secured the ends of the rope or cable bail 13, such rope being held in the bores by means of Babbitt metal. Disposed within the shell, and receiving the

50 boss 11 within its lower coils, is a coil spring

14, and disposed in concentric relation outwardly of the spring 14, within the shell, is a slightly larger spring 15, the lower ends of both of said springs resting on the bottom wall of the shell. Disposed in the upper end 55 of the shell 10 is a hollow block or follower 16, said block having a downwardly extending hollow boss 17 extending from the center of its lower end and lying within the upper end coils of the spring 14. The upper wall of 60 the block is provided with an opening 18 which alines with the opening through the boss 17, to receive the polish rod 19 therethrough, said rod also passing upwardly through the lower boss 11, as clearly seen in 65 the sectional view, Figure 2. Secured on the polish rod 19, above the block 16, is a collar or clamp 20, which serves to maintain the block in proper contact with the upper ends 70 of the springs 14 and 15, whereby said springs are maintained under a certain degree of compression, and whereby the block is held partly within the upper end of the shell. The upper, or closed portion of the bail 13 is engaged 75 over an end of the walking-beam 21, while the lower end of the rod 19 extends into the well casing, not shown, but which will be readily understood.

The shell is filled with oil, so that the springs 14 and 15 are completely submerged, 80 whereby to maintain said springs in proper condition, and to prevent collapse or going dead thereof. Also, some of the oil will be splashed into the bore of the boss 11, and into the bore of the boss 17, whereby to insure 85 the proper lubrication of the rod 19, and the smooth movement thereof through the parts, with which it is associated.

From the foregoing it will readily be seen 90 that, when the end of the walking-beam 21 moves upwardly, the shell 10 will be lifted, through the medium of the bail 13, the weight of the rod 19, and the expansive resistance of the springs 14 and 15 serving to prevent a sudden upward jerk on the rod.

Where a well is of great depth, a double shock absorber is used, such as illustrated in Figures 4, 5, and 6. In this construction there is provided a double-barreled casing, which includes the two parallel cylinders 22, 100

connected by the intermediate neck portion 23, such neck portion being hollow whereby to establish communication between the cylinders. Rising from the center of the bottom wall of the neck portion 23 is a hollow boss 24, through which the polish rod 25 is slidably disposed. Disposed in each of the cylinders are the pair of coil springs 26 and 27, the latter being slightly smaller than the former and disposed concentrically therewithin. Disposed in the upper portion of the casing is the hollow follower block 28, said block having the circular portions 29 arranged to slide vertically within the respective cylinders, and bearing on the upper ends of said springs, said portions 29 each being formed with a depending projection or boss 30 receiving the upper ends of the springs. The outer sides of the cylinders are formed 20 with the longitudinal bores 31, receiving the ends of the cable bail 32, said bail having its bight portion adapted for proper connection with an end of a walking-beam, in a manner similar to that shown in connection with the 25 first form of the shock absorber.

The cylinders, together with the neck portion of the casing, are filled with oil, whereby the springs are completely submerged therein, the boss 24 being of such a height as to 30 maintain the oil at the desired level therein. The upper end of the polish rod, above the follower block, is provided with a clamp 33, which is arranged to bear on the upper face of said block, whereby to urge the same downwardly, against the tension of the springs, for the purpose of absorbing the jar and shock incident to the lifting of the well tool, as well as the lowering thereof.

What is claimed is:

40 A shock absorber for an oil well pump rod comprising a lubricant containing shell having its upper end open and having an upwardly extending hollow boss on its bottom wall for maintaining the lubricant at a pre-
45 determined level and for receiving a polish rod therethrough, a follower block in the upper open end of the shell and having a downwardly extending hollow boss on its lower end, concentric coil springs disposed
50 within the shell, the inner of the springs receiving the said bosses in its opposite ends, the shell having longitudinal tapering bores in its opposite sides, and a cable in the form
55 of a bail disposed above the shell and having its ends wedgingly secured within said longitudinal tapered bores.

In testimony whereof, I affix my signature.
FRANK C. BAKER.
